UNITED STATES PATENT OFFICE

124,893

DESIGN FOR A GLASS SHIELD FOR FLUORESCENT LAMPS

Hugh J. Claspy, Monaca, Pa., assignor to The Phoenix Glass Company, Monaca, Pa., a corporation of West Virginia

Application August 3, 1940, Serial No. 94,183

Term of patent 14 years

To all whom it may concern:

Be it known that I, Hugh J. Claspy, a citizen of the United States, residing at Monaca, in the county of Beaver, State of Pennsylvania, have invented a new, original, and ornamental Design for a Glass Shield for Fluorescent Lamps, of which the following is a specification, reference being had to the accompanying drawing, forming a part thereof.

Figure 1 is an end elevational view of the glass shield having approximately half of the end broken away for convenience of illustration, showing my new design, and Fig. 2 is a side elevational view thereof.

I claim:

The ornamental design for a glass shield for fluorescent lamps, as shown.

HUGH J. CLASPY.
